EXPANSION CHAMBER FOR REFRIGERATING APPARATUS

Application filed July 22, 1925, Serial No. 45,395. Renewed January 20, 1928.

This invention relates to improvements in refrigerating apparatus and particularly to an improved expansion chamber for such apparatus.

5 One of the objects of the invention is to provide an expansion chamber constructed in sections so that the capacity of the chamber may be readily increased by adding an additional section or sections whereby the 10 capacity of the expansion chamber may be in proper proportion to the space to be cooled; a further and more specific object in this connection being to provide a sectional expansion chamber in which one of the sections only is arranged to carry the usual controlling devices for the refrigerant, to which section may be connected one or more additional sections as needed, with the chambers of the sections in communication with each 15 other.

A further object of the invention is to provide an expansion chamber of simple form which will furnish a maximum amount of heat absorbing surface without the employment 20 of fins or other heat absorbing aids, and also a chamber in which the refrigerant may be in direct contact with the walls which form the heat absorbing surface of the chamber.

25 Referring to the drawings:

Fig. 1 is a side elevation of the improved expansion chamber.

Fig. 2 is a front elevation of the same.

Fig. 3 is a vertical section taken on the 30 line 3—3 of Fig. 2.

In the development of refrigerating apparatus of the type in which the expansion chamber is located in a refrigerating box such as is used for domestic and other purposes it has been found desirable to employ expansion chambers of the direct expansion type which will not only possess the quality of efficiently cooling the box but also have provision for freezing ice for domestic use.

Use has been made of directly exposed coils which have the necessary box cooling qualifications but lacked the facility for making ice. Use has also been made of a box-like expansion chamber in connection with fins arranged on the outer walls of the chamber

to provide sufficient heat absorbing surface, such an expansion chamber being efficient for cooling and ice making but being of an expensive construction due to the fins. Another disadvantage of this type of expansion chamber is that the heat absorbing surfaces are too remote from the refrigerant to secure the best results. A further objection to the latter arrangement is that it is necessary either to make these expansion chambers of 55 different sizes for cooling boxes of different capacity or to install in the boxes of larger capacity two or more of such chambers, each equipped with its individual regulating devices, all of which results in an expensive 60 equipment. In order to overcome these disadvantages and to provide an expansion chamber which is not only efficient for cooling and ice making, but in which the capacity may be readily increased in an inexpensive 65 manner to suit the size of the refrigerating box in which the apparatus is to be installed, and also to bring the heat absorbing surfaces 70 in more intimate relation with the refrigerant, the following arrangement has been devised:

Referring to the drawings, there is shown an expansion chamber constructed of three sections 1, 2 and 3 although it will be understood that the number of sections may be 75 increased or diminished to suit conditions. Each section is cast to provide an inner open space 4 surrounded by the walls of a chamber 8, the walls being only of a thickness consistent with proper strength and of a uniform character throughout. These open spaces receive a box 6 open at its forward end in which may be placed trays 5 to receive commodities to be frozen, a suitable removable cover 7 being provided at the front 80 of the chamber thus formed. Each section constitutes an independent expansion chamber, the walls of which are provided with aligned threaded openings 9 to receive couplings so that the respective chambers may be 85 connected both at the top and bottom. To connect the sections, there is shown an ordinary standard reversely threaded coupling 10, but any other suitable form of connection 90 may be employed so long as it is of a char- 100

acter to leave the sections in spaced apart relation. The openings 9 of the rearmost section are closed by plugs 11 and the front wall of the section 1 has a sand opening closed by a plug 11'.

5 One of the sections only is equipped with controlling devices for the refrigerant, this section being the one indicated by the reference character 1. To this section 1 the incoming line 12 from the condenser is connected at the point indicated by 13 and the outgoing return line (not shown) leading to the compressor is connected at the point indicated at 14. A needle valve 15 controls 10 the inlet 13, this needle valve being supported in the usual way upon a pivoted float operated arm 16 provided with a float 17. This section 1 is provided with a removable cap 18 which carries the float operated valve and 15 has the inlet opening 13.

By this construction it will be seen that the capacity of the expansion chamber may be readily and inexpensively increased by simply adding an additional section or sections. For small refrigerating boxes, a single section 1 will suffice, while for larger sized boxes another section 2, a third section 3, or additional sections constructed like 2 and 3, may be readily added. The chambers 8 20 of the respective sections being all connected together form in effect a single expansion chamber which may be controlled by the valve mechanism located in the section 1.

Further, it will be seen that due to the 25 spaced-apart arrangement of the sections the front and rear walls of each section as well as the top and bottom walls are all exposed to the air of the refrigerating box and that the refrigerant in the chambers is in direct 30 contact with these walls which arrangement furnishes an adequate heat absorbing surface without the addition of fins or other heat absorbing aids.

Having thus described my invention, I 35 claim:

1. An expansion element for refrigerating apparatus having a section formed with an open space and a continuous chamber about said space, said chamber constituting 40 a receptacle for the refrigerant and having a passage leading thereto for the entrance of the refrigerant, the upper portion of said chamber being of sufficient area to receive float-operated valve mechanism for controlling 45 said passage, and float-operated valve mechanism located in said portion of said chamber, said section having means for readily connecting therewith another section similar thereto with respect to the open space 50 and the surrounding chamber, with the chambers in communication, whereby the capacity of said element may be increased.

2. An expansion element for refrigerating apparatus having a section formed with a central open space and a continuous chamber

about said space, said chamber constituting a receptacle for the refrigerant and having a passage leading into the upper portion thereof for the entrance of the refrigerant, said upper portion of said chamber being of sufficient area to receive float-operated valve mechanism for controlling said passage, and float-operated valve mechanism located in said portion of said chamber, said section having means for readily connecting therewith another section similar thereto with respect to the open space and the surrounding chamber, the connection forming communications between said chambers, whereby the capacity of said element may be increased.

3. An expansion element for refrigerating apparatus having a section formed with an open space and a continuous chamber about said space, said chamber constituting a receptacle for the refrigerant and having a passage leading thereto for the entrance of the refrigerant, the upper portion of said chamber being of sufficient area to receive float-operated valve mechanism for controlling said passage, and float-operated valve mechanism located in said portion of said chamber, the thickness of the outer walls of said chamber being of a uniform character and sufficient only to give required strength, said section having means for readily connecting therewith in spaced apart relation thereto another section similar thereto with respect to the open space, the surrounding chamber and thickness of the walls, said connections forming communications between the chambers of the respective sections, whereby the capacity of said element may be increased.

4. An expansion element for refrigerating apparatus having a section formed with an open space and a continuous chamber about said space, said chamber constituting a receptacle for the refrigerant, the upper portion of said chamber being of sufficient area to receive float-operated valve mechanism and having an opening large enough to permit the insertion of said mechanism, a cap for closing said opening having a passage for the entrance of the refrigerant, float-operated valve mechanism carried on the inner side of said cap, said section having means for readily connecting therewith another section similar thereto with respect to the open space and the surrounding chamber, with the chambers in communication, whereby the capacity of said element may be increased merely by the addition of another section devoid of valve mechanism.

5. A refrigerating unit for refrigerating machines, comprising a plurality of hollow sections connected to contain a refrigerant, said sections having aligned openings forming the chilling compartment of the unit, said unit having refrigerant inlet and outlet openings above said chilling compartment, and

- valve means in one of said sections for controlling the supply of refrigerant to the sections, through said inlet opening, the refrigerant outlet opening being above the normal liquid level set by the valved inlet opening. 5
6. A refrigerating unit for refrigerating machines, comprising a plurality of hollow sections connected together to contain a refrigerant and to provide a communicating passage between them, and a float valve located in one of said sections for controlling the supply of refrigerant to the sections, the latter being formed to provide a chilling compartment for the unit, said unit having a refrigerant outlet opening above the normal liquid level established by said float valve. 10
7. An expansion element for refrigerating apparatus consisting of a plurality of sections, each having a chamber, means for connecting said sections together with the chambers of the sections in communication with each other, each section forming the boundary of an open space, with all the open spaces aligned to form a chilling compartment, means for admitting refrigerant to the chambers of said sections, an outlet for the refrigerant located above the maximum liquid level thereof and valve means for fixing the level of the refrigerant in the connected sections. 15
8. An expansion element for refrigerating apparatus consisting of a plurality of sections connected together, each having a chamber, with the chambers in communication, each section forming the boundary of an open space, with all the open spaces aligned to form a chilling compartment, means for admitting refrigerant to said chambers, an outlet for the refrigerant located above the maximum liquid level of said refrigerant and a float valve for fixing the level of the refrigerant in the connected sections. 20
9. An expansion element for refrigerating apparatus consisting of a plurality of sections connected together, each having a chamber, said chambers being in communication, each section forming the boundary of an open space, with all the open spaces aligned to form a chilling compartment, means for admitting refrigerant to said chambers and controlling its level therein, and an outlet for the refrigerant located above the maximum liquid level of said refrigerant, said admission means and outlet being located on the same section. 25
10. An expansion element for refrigerating apparatus consisting of a plurality of connected sections each having a chamber, with the chambers in communication with each other, each section forming the boundary of an open space, with all the open spaces aligned to form a chilling compartment, an inlet associated with said element for supply- 30
- ing unexpanded refrigerant thereto, valve means associated with said inlet for automatically controlling the supply of refrigerant to the expansion element, and a suction outlet for said chambers associated with said element, and arranged to permit the passage of expanded refrigerant therefrom. 70
11. An expansion element for refrigerating apparatus consisting of a plurality of connected sections each having a chamber, with the chambers in communication with each other, each section forming the boundary of an open space, with all the open spaces aligned to form a chilling compartment, a supply inlet associated with one of said sections to supply unexpanded refrigerant to the chamber thereof, valve means associated with said inlet for automatically controlling the supply of refrigerant to the expansion element, and a suction outlet associated with the same section and in communication with the chamber thereof, and arranged to permit the passage of expanded refrigerant therefrom. 75
12. A refrigerating unit for refrigerating machines, comprising a plurality of hollow sections connected together to contain a refrigerant, said sections having aligned openings forming the chilling compartment of the unit, said unit having refrigerant inlet and outlet openings, and a valve for controlling the supply of refrigerant to the sections through said inlet opening, the refrigerant outlet opening being above the normal liquid level set by the valved inlet opening. 80
13. An expansion and refrigerant control element for refrigerating apparatus consisting of a plurality of sections cooperating together to form the boundary of a tube-like chilling compartment, said sections having refrigerant-receiving chambers therein, means for connecting said sections together with said refrigerant-receiving chambers in communication with each other, means for admitting liquid refrigerant to the chambers of said sections, valve means associated with said last-mentioned means for automatically controlling the supply of refrigerant to said sections, and a suction outlet for said chambers arranged to permit the discharge of refrigerant in gaseous form only from said element. 85
14. An expansion and refrigerant control element for refrigerating apparatus consisting of a plurality of sections cooperating together to form the boundary of a tube-like chilling compartment, said sections having refrigerant-receiving chambers therein, means for connecting said sections together with said refrigerant-receiving chambers in communication with each other, means for admitting liquid refrigerant to the chambers of said sections, valve means for controlling the liquid level of refrigerant within said element, and a suction outlet arranged to per- 90

mit the discharge of refrigerant in gaseous form only from said element.

15. An expansion and refrigerant control element for refrigerating apparatus consisting of a plurality of sections cooperating together to form the boundary of a tube-like chilling compartment, said sections having refrigerant-receiving chambers therein, means for connecting said sections together 10 with said refrigerant-receiving chambers in communication with each other, and means arranged to admit volatile refrigerant in liquid form to the chambers of said sections and to permit the discharge of said refrigerant in gaseous form only from said element.
- 15 16. In a mechanical refrigerating apparatus of the compressor-condenser-flooded-expander type, an expansion unit comprising a plurality of hollow sections for liquid 20 refrigerant, the interiors of said sections being connected in operative communication, one of said sections having a liquid refrigerant inlet, control valve means operatively positioned within said section for controlling the flow of liquid refrigerant to said expansion unit, and a suction outlet for said sections arranged to permit the discharge of refrigerant in gaseous form only from said unit.
- 30 17. In a mechanical refrigerating apparatus of the compressor-condenser-flooded-expander type, an expansion unit comprising a plurality of hollow sections for liquid refrigerant, the interiors of said sections being 35 connected in operative communication, one of said sections having a liquid refrigerant inlet, control valve means operatively positioned within said section, a float within the unit cooperating with said control valve 40 means for preventing liquid refrigerant from rising above a certain level in said expansion unit, and a suction outlet for said sections arranged to permit the discharge of refrigerant in gaseous form only from said unit.
- 45 In testimony whereof, I have hereunto set my hand this 14th day of July, 1925.

CHARLES F. GARDNER.
